UNITED STATES PATENT OFFICE.

MATTHEW A. FORD, OF ROCKFORD, ILLINOIS.

COLLAPSIBLE STAND.

1,199,258.

Specification of Letters Patent. Patented Sept. 26, 1916.

Application filed May 24, 1915. Serial No. 30,090.

To all whom it may concern:

Be it known that I, MATTHEW A. FORD, a citizen of the United States, residing at Rockford, in the county of Winnebago and State of Illinois, have invented certain new and useful Improvements in Collapsible Stands, of which the following is a specification.

This invention relates in general to collapsible stands or supports and has more particular reference to stands adapted for supporting cooking utensils above a camp fire.

One of the primary objects of my invention is to provide a stand or support of novel construction which may be used by hunters, canoeists and other sportsmen for supporting or suspending cooking utensils over a camp fire, and which when not in use 20 may be folded or collapsed into a compact form so that it will occupy but a small space and be convenient to transport.

Another object of my invention is the provision of a stand of the above character of such improved design as to insure sufficient strength and durableness and withstand the heat to which the stand is subject during use.

Other and more specific objects of my invention are to provide a hollow casing which 30 forms part of the stand and is adapted to enclose the legs and hangers when they are not in use, to provide a novel means for supporting the hangers in operative position, to provide cap members for closing the ends 35 of the casing when the legs and hangers are disposed therein, so that the casing has a finished appearance and the contents thereof are prevented from being displaced, and to provide novel means for locking the caps 40 against being displaced from their closed positions.

Referring to the drawings, Figure 1 is a vertical longitudinal view through my improved stand, showing it in operative position; Fig. 2 is also a longitudinal sectional view through the stand, but showing it in collapsed arrangement; Figs. 3 and 4 are cross-sectional views taken on the lines 3-3 and 4-4, respectively of Fig. 1; and 50 Figs. 5 and 6 are cross-sectional views taken on the lines 5-5 and 6-6 of Fig. 2.

The stand comprises in general a tubular casing or body 1 adapted to be supported by legs 3 which are slidable into the body, 55 an extendible rod 4 slidably mounted in the casing and provided at its upper or outer

end with a plurality of hangers 5, which are movable with the said rod into the body, and caps 6 and 7 adapted to close the open ends of the body when the legs and hangers have been moved thereinto, the cap 6 being integral with the hanger-supporting means.

The above reference characters designate in general their respective elements.

The body 1 is formed preferably of a piece 35 of tubing of suitable gage. The castings, designated in general by reference characters 27 and 8 are each pivotally secured as by means of suitable pins, in the body adjacent to an end thereof and provided with 40 a central bore 9 and a plurality of radially spaced apertures extending longitudinally through the castings. These apertures, which are of different widths, the wider being 45 designated by the reference character 10 and the narrower by the character 11, are arranged so that their apertures are in longitudinal alinement. Each casting is cone shaped at one end, providing depressed seats 50 12, the purpose of which will be presently 55 apparent. It will be noted that these cone shaped ends are located at the inside of the body and that the casting 7 is spaced within 60 the top end of the body.

The rod 4 has fixedly secured to its upper 65 end, the cap 6 which is adapted to cover the top opening of the body when the rod is slid to its innermost position. Upon the underside of the cap are pivotally mounted 70 three arms or hangers 5 arranged so that 75 they will extend radially and horizontally from the rod and so that they may fold down adjacent thereto. Each hanger is provided with suitable notches on its upper face 80 to receive and hold from displacement the 85 handle or bail of a cooking utensil or any other article to be supported over a fire. One of the hangers is articulated at 13 so 90 that it will be swung sidewise to various positions. A ring 14 slidably mounted on 95 the rod is adapted to be moved into abutting relation with the inner ends of the hangers to hold the same in supporting position. Means are provided for holding the rod in 100 extended position and comprise a manually 105 operable slide or latch 15 adapted to engage in an annular groove 16 in the rod.

When it is desired to move the hangers into the body, the ring 14 is released by 110 slightly raising the outer ends of the hangers, thereby permitting the ring to slide down the rod and allowing the hangers to

be folded down. The latch 15 is then retracted and, the outer ends of the hangers having been entered in the openings 10, the rod 5 and hangers may be slid into the body 5 until the cap 6 abuts against the top thereof, the outer ends of the hangers entering the openings 10 in the casting 8, as shown in Fig. 2.

The legs 3 passing through the apertures 10, 11 of the lower casting, are provided at their inner ends with radially projecting pins 17, which by abutting against the faces 12 limit the extension of the legs from the body. The legs in their extended position are disposed in slots 18 formed in the body as a continuation of apertures 11. Since the pins 17 serve as a fulcrum for the legs and the inner ends of the slots 18 form rests against which the legs abut, the legs are 20 precluded against collapsing and are so arranged that they sustain the body and hangers in upright position. It will be apparent that the legs may be slid entirely into the body and the pins of the legs abut 25 against the faces 12 of the upper casting, as shown in Fig. 2.

When the hangers and legs are positioned within the body, a bottom cap 17 provided with a flanged edge for covering the slots 30 18 may be placed over the bottom end of the body. This cap is provided with means adapted to interlock the cap with the inner end of the rod 4 so as to preclude both the rod and hangers and, consequently the cap 35 6, against being withdrawn from the body and to interlock the bottom cover against removal. This locking means comprises a spring-pressed latch 20 carried by the cap 19 and engageable in an annular groove in 40 the inner end of the rod 5 and releasable from locking engagement by actuation of a finger 21 bent downwardly from the latch member through a slot in the cover so as to be accessible from the outside thereof. 45 It should be understood that I do not limit myself to the particular form of locking device illustrated for holding the rod in operative position and for locking the rod and both covers against removal, since various other forms of locking devices might 50 be equally well employed. It will also be apparent that while I have illustrated one practical embodiment of my invention, various changes in the structural details thereof might be resorted to without departing from the spirit of the invention or sacrificing any of its material advantages.

I claim:

1. A device adapted for supporting cooking utensils and other articles over a camp fire, comprising a tubular body, legs for supporting the same in upright position and being movable into the body, and means mounted in and projecting above the upper end of the body and provided at its upper

end with laterally extending hangers foldable into close relation to the said means and being movable therewith into the body, one of said hangers being so articulated intermediate its ends that its outer end may be swung laterally upon and with respect to its inner end to different positions in which to support articles.

2. A device adapted for supporting cooking utensils and other articles over a camp fire, comprising a tubular body, legs for supporting the same in upright position, hangers sustained by and projecting radially from the body, said legs and hangers being movable into the body, and caps so adapted to close each end of the body when said legs and hangers have been moved thereinto, and a common means for holding said caps against being removed, said means being operable from the exterior of the device for permitting the caps to be removed.

3. An article of the character described comprising a tubular body inclosing supporting legs and hangers extendible each from a separate end of the body to operative positions, caps adapted to cover the ends of the body when said legs and hangers are disposed therein, and a common means for locking both caps against displacement from their end covering positions.

4. A stand adapted for supporting articles over a camp fire, comprising a tubular body, legs mounted in the body for supporting the same in upright position, a cap disposed above the body and adapted to cover the upper end thereof, means fitting telescopically in the body and connected to the cap for supporting the same in a position spaced above the body, a plurality of hangers pivotally mounted on the cap and extending laterally therefrom providing means upon which cooking utensils and other articles may be hung, means for maintaining said arms in fixed supporting position and permitting the arms to be folded into close relation so that they may fit in the top end of the body and be moved within the same, followed by the cap which closes the top end of the body.

5. A stand adapted for supporting articles over a camp fire, comprising a tubular body, legs mounted in the body for supporting the same in upright position and being slidable through the lower end of the body to positions within the same, a cap adapted to cover the upper end of the body and provided with laterally extending hangers adapted to support cooking utensils and other articles, means for holding the cap elevated above the body with said hangers in supporting position, said hangers and said cap-supporting means being movable through the top opening in the body to positions within the same whereby the cap will cover the top opening, and a bottom cap

adapted to cover the bottom opening after the legs have been moved into the body, said bottom cap being provided with means engageable with said cap-holding means for 5 locking both caps against outward displacement.

6. In an article of the character described, the combination of a tubular body open at both ends, supporting legs movable from 10 supporting position into the body through the lower end thereof, supporting means mounted in the top end of the body and provided at its outer end with radially extending hangers adapted to be moved with the 15 supporting means into the body and provided also with a cap adapted to close the top end of the body after said supporting means and hangers have been positioned within the body, and a cap adapted to cover 20 the lower end of the body and provided with means for locking both caps against outward displacement.

7. In an article of the character described, the combination of a tubular body, a casting 25 secured within the same adjacent to each

end thereof, each casting being provided with a central bore and a plurality of radially spaced apertures extending longitudinally through the casting, the apertures in said castings being in longitudinal alignment, supporting legs slidably mounted in certain apertures in one of the castings so as to be retractable to positions entirely within the body, a rod slidably mounted in the bore of the other casting and provided at its outer end with a cap adapted to close the adjoining end of the body and with pivotally mounted hangers adapted to fold into close relation to the rod and pass through certain apertures in the last named 40 casting into the body by sliding of said rod into the same, the inner end of said rod being movable into the bore of the first named casting when said rod and hangers have been positioned within the body, and 45 means for locking said rod against being withdrawn from said position within the body.

MATTHEW A. FORD.
